UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,101,765.

Specification of Letters Patent. Patented June 30, 1914.

Original application filed June 30, 1903, Serial No. 163,704. Divided and this application filed December 18, 1912. Serial No. 737,381.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

My invention relates to typewriting machines, the present application being a division 10 of my co-pending application, No. 163,704, filed June 30, 1903.

The present invention relates more particularly to the type-bars and actuating 15 means therefor.

The finger keys are on the forwardly extending arms of bell crank levers, which also have depending arms connected through links to pendent levers at the rear of the 20 machine. The type-bars which extend forwardly from their fulcrum rod are connected through links to said pendent levers.

The accompanying drawing is a sectional elevation view, partly diagrammatic, of a 25 structure embodying my invention as used in a typewriting machine.

The framework of the machine comprises walls forming a base 1. Forwardly extending type-bars 4 are pivoted at their rear 30 ends upon a curved fulcrum rod 5 mounted in a segment 6, and strike rearwardly against a platen 7. The segment is radially slotted at 8 to receive the type-bar hubs. Each type-bar is provided with a 35 lower-case type 9 and an upper-case type 10, the latter being uppermost when the type-bar is in printing position, although this relation may be reversed within the scope of certain features of my improvements, and 40 the type-bars may be otherwise mounted. The type-bars may be operated by any suitable means, as for instance pull-links 11, extending rearwardly and downwardly from the type-bars, pendent levers 12 connected 45 between their ends at 13 to said links, a horizontal rod 14 whereon said levers are fulcrumed at their upper ends, horizontal links 15 connected at 16 to the lower ends of said levers and extending forwardly, and 50 key-bearing bell cranks fulcrumed upon a transverse rod 17 and having pendent arms 18 connected at 19 to said links 15, and forwardly extending arms 20 bearing the keys

21. Returning springs as 22 may be provided for the type actions. 55

Various modifications may be resorted to.

The platen may be mounted in any ordinary way, as for instance in a platen frame to shift up and down in a non-shifting paper carriage. The mechanism for feeding the 60 carriage, which supports the platen, may be of any ordinary kind. For the sake of illustration it is shown as comprising upright detent and feeding dogs 107 and 108, coöperating with a rack 106 connected to 65 travel with the carriage, the feeding dog 108 being normally in engagement with the rack. The dogs are mounted on one end of a suitably supported rock shaft 112 provided with an operating arm 113, which at 70 its rear end is pivoted at 116 to a pendent link 117, whereby the arm is operated. At its lower end said link is pivoted at 118 to the forward end of a rocker arm 119, which projects forwardly from a horizontal transverse rock shaft 120. A universal bar 121 is mounted upon the tops of a pair of arms 122 which rise from said rock shaft, and said bar lies in rear of the levers 12 of the type actions, so as to be operated thereby, 80 the described universal bar frame being provided with a returning spring 123.

Variations may be resorted to within the scope of the invention, and portions of the improvements may be used without others. 85

Having thus described my invention, I claim:

1. In a front-strike writing machine, the combination with rearwardly striking type-bars and a platen, of pull links extending 90 rearwardly from the type-bars, pendent levers at the rear of the machine to which said links are connected between the lever ends, links extending forwardly from the lower ends of said levers, and key-bearing 95 bell-cranks connected to the forward ends of said links.

2. In a typewriting machine, the combination of a rearwardly striking pivoted type-bar, a platen, pendent levers at the rear of the frame, a bell-crank key lever having a key on its forwardly extending arm pivoted forward of the type-bar pivot, and links extending rearwardly from the key lever and type-bar to said pendent levers. 100 105

3. In a typewriting machine, the combi-

nation of a type-bar segment, type-bars pivotally supported therein and having type bearing arms extending upwardly from their pivots, bell-crank key levers pivoted in front of said segment and having depending arms, links extending rearwardly from said depending arms, links extending rearwardly and downwardly from the upwardly extending arms of the type-bars, and pendent levers operatively connected below their fulcrums to all of said links.

4. In a typewriting machine, the combination of a machine frame, pendent levers supported at the rear of said frame, type-bars, key-levers connected to the lower ends of said pendent levers and connections from the pendent levers to the type-bars, said connections engaging said pendent levers between their fulcrums and their lower ends.

5. In a typewriting machine, the combination of type-bars, bell-crank key levers pivoted adjacent to the type-bar pivots, vertically disposed pendent levers located at the rear of the machine, links connecting said last-named levers to the key levers, and means connecting the type-bars to the vertically disposed levers.

6. In a typewriting machine, the combination of a machine frame, vertically disposed pendent levers located at the rear of the frame, bell-crank key levers having depending arms, links connecting said arms to the lower ends of said first-named levers, type-bars, and links connecting the type-bars to said first-named levers below the fulcrums of the latter.

7. The combination of keys forming the keyboard of the typewriter, levers carrying said keys, said levers fulcrumed in rear of the keys and about on a level therewith, forwardly and downwardly extending arms on said levers, links connected to said levers at their lower ends and extending rear-

wardly, pendent levers to which said links are also connected, type-bars, and connecting means between said type-bars and said pendent levers. 45

8. The combination of rearwardly striking type-bars, pull links connected to said type-bars and extending rearwardly therefrom, pendent levers fulcrumed in rear of the type-bars, said links at their rear ends being pivoted to said levers between the ends of the levers, bell-cranks mounted in front of the type-bars and comprising forwardly extending arms bearing keys, said bell-cranks also comprising downwardly extending arms, and thrust links extending from said downwardly extending arms to the lower ends of said pendent levers. 50 60

9. The combination of rearwardly swinging type-bars, pull links connected to said type-bars and extending rearwardly therefrom, pendent levers fulcrumed in rear of the type-bars, said links at their rear ends 65 being pivoted to said levers between the ends of the levers, key-bearing levers, and thrust links extending rearwardly from said key-bearing levers to the lower ends of said pendent levers. 70

10. The combination with a series of key-bearing bell-cranks having arms pendent from their pivots, of type-bars overlying the bell-cranks, and connections from the type-bars to the lower ends of said bell-cranks; said connections including links and straight, pendulously pivoted levers, the links being both connected to the lever on the same side of the lever pivot, said levers being arranged to vibrate in approximately the same direction as the points of the type-bars to which they are connected. 75 80
